Primary Examiner — Sheryl Lane*Assistant Examiner* — Ieisha Price*(74) Attorney, Agent, or Firm* — Shannon L Warren(57) **CLAIM**

The ornamental design for log tongs, as shown and described.

DESCRIPTION

FIG. 1 is a top view of log tongs;

FIG. 2 is an enlarged front perspective view thereof;

FIG. 3 is a side view thereof;

FIG. 4 is an enlarged rear perspective view thereof;

FIG. 5 is a top view thereof, shown in a closed position;

FIG. 6 is a top view thereof, shown in a partially open position; and,

FIG. 7 is a top view thereof, shown in a completely open position.

The broken lines in the drawings illustrate portions of the log tongs and form no part of the claimed design.
